UNITED STATES PATENT OFFICE.

OTTO PANKRATH, OF RAUNHEIM, MAIN, GERMANY.

CENTRIFUGAL MACHINE.

1,387,661.

Specification of Letters Patent. Patented Aug. 16, 1921.

Application filed May 1, 1920. Serial No. 378,280.

To all whom it may concern:

Be it known that I, Dr. OTTO PANKRATH, a citizen of the German Republic, and residing at Raunheim, Main, Germany, have invented certain new and useful Improvements in Centrifugal Machines, of which the following is a specification.

The hitherto known continually acting centrifugal machines with cone-shaped or wing-shaped centrifugal surfaces all suffer from the drawback that the material to be treated, for instance sugar filling-mass, is non-uniformly dried, or that their capacity is unsatisfactory. According to the present invention, said drawbacks are to be overcome by the arrangement of a device, which, while acting itself in a centrifugal way, supplies or throws the material to be treated in thin layers and in a uniform distribution upon the centrifugal surfaces of the machine. Depending on the extent of distribution intended, the device may be of modified constructions in its details.

The annexed drawing shows some suitable constructional forms of the improved arrangement:

Figure 1 shows a vertical central section through a centrifugal machine having three cone-shaped centrifugal surfaces, to which the distributor is attached;

Figs. 2 and 3 are respectively a vertical central section and a plan view of a modified construction of distributor;

Figs. 4 and 5 are respectively a front view, partly in section, and a plan view of a further modification of distributor;

Fig. 6 is a vertical central section through a centrifugal machine having wing-shaped centrifugal surfaces, with the same type of distributor as in Fig. 1;

Figs. 7 and 8 are respectively a vertical central section and a plan view through another type of centrifugal machine with wing-shaped centrifugal surfaces.

Referring to Fig. 1: The cones K^1 , K^2 , K^3 are keyed on the hollow axle B. Through the latter passes a rotary shaft A, which carries the distributor V and which receives different circumferential speed to that of the axle B. The filling-mass flows through three pipes R^1 , R^2 , R^3 to the three superposed compartments of the distributor V and is thrown onto the cones K through the three annular slots O^1 , O^2 , O^3 in said distributor. The cones K are fitted with strainers upon which settle the crystals while the syrup is col-

lected on the cone surfaces and escapes through the bottom openings L.

The supply to the pipes R can be easily controlled in such a way that all three compartments of the distributor V and thus all three cones K receive equal quantities of filling-mass. From the slots O of the distributor, the filling-mass is thrown in tangential direction, whereby all lumps are divided to crystal size, and, owing to the different speeds of shaft A and axle B, are still farther spread upon the cones K. The greater the difference between the speeds of shaft A and axle B, the finer and thinner is the filling-mass distributed upon the cones and the more can be supplied and sufficiently thrown out. The capacity of the cones K depends thus upon the efficiency of the distributor V. If the cohesion of the filling-mass lumps is very large, it will require a stronger effect of the distributor than vice versa. In this case, behind the first distributor, a second and third distributor can be inserted, and each distributor can be designed as a drum with strainers, so that the filling-mass is not distributed and spread at a time but in stepwise fashion. For instance, on the hollow axle B a second hollow axle of different speed to that of axle B may be mounted and also fitted with three cone-surfaces which, of course, are so large that the filling-mass from the cones K can be delivered upon the same.

Other forms of distributor V are shown in Figs. 2 to 5. Instead of the filling-mass being supplied through a plurality of pipes R, it is divided by the distributor itself into three portions corresponding to the three cones K, so that one supply-pipe R only is required.

In Fig. 2, the distributor is cone-shaped. The filling-mass from the cup T underneath the pipe R is thrown upon the walls of the cone M and flows down the same. As shown in Fig. 3, the walls of the cone M are interrupted by three rows of alternately arranged slots O^1 , O^2 , O^3 , of which the uniform arrangement and width results in a correspondingly uniform distribution of the filling-mass upon the cones K^1 , K^2 , K^3 . For this purpose, the cone surface M (Fig. 3) is divided into twelve radial sections of equal size, of which always each three succeeding sections at three different distances from the center have slots O^1 , of which the width corresponds to the width of the sec-

sition at the respective place of the cone surface M^2 . Now, said three slots are arranged four times, that are together twelve slots. Owing to said division, all said slots allow a 5 passage of approximately equal quantities of filling-mass therethrough, and furthermore that quantity which is not taken-up by the slots of row O^1 must flow either through those of row O^2 or O^3 . Of course, 10 the slots O may also be dimensioned and distributed in any other way. The object of the division described is to supply all three cones K , as far as possible, with equal 15 quantities of filling-mass and further to uniformly spread the latter upon each single cone K .

In Figs. 4 and 5, the distributor is drum-shaped. The cylindrical walls have three rows of slots O^1 , O^2 , O^3 each with four slots, 20 that are together twelve slots. The drum-space is subdivided by partitions Q into twelve chambers of equal size of which each four are in communication with the slots O^1 to O^3 inclusive. The slots O numbered 1 25 supply the filling-mass onto the cone K^1 , and those numbered 2 and 3 onto the cones K^2 and K^3 respectively.

The distributors described, for cone-shaped centrifugal surfaces, can also be applied to other centrifugal machines, for instance such with wing-shaped centrifugal surfaces, as shown in Fig. 6, where a distributor of the construction shown in Fig. 1 serves for the supply of wings F . Here, 30 however, the filling-mass meets only three places of the centrifugal surfaces. Preferably, the filling-mass is to be distributed on the whole width of the wings, as shown in Figs. 7 and 8. The wings are here subdivided into an upper and a lower half F^1 and F^2 which lead onto the cones M^1 and

M^2 of the distributor. Corresponding to the arc-shape of the sixteen wings F , the cones M are interrupted by arc-shaped slots S . The proportion between the number of 45 wings and their width is so chosen that always the upper end of a slot S in the cone M covers the lower end of the adjacent slot, so that the whole filling-mass, which is thrown from the distributor V onto the cone 50 M , must, when slipping-down, pass through the slots upon the sixteen wings, and that upon the whole width of the same. For instance, when drawing in Fig. 8 a radius to the lower end of a slot, the same intersects 55 the upper end of the adjacent slot. As the filling-mass, when slipping-down the cone M , follows always the sides of the same, which in plan view (Fig. 8) appears as a radius, that quantity of the filling-mass, which 60 has flown along the upper end of a slot S , will be safely caught by the lower end of the adjacent slot.

What I claim, is:

In a centrifugal machine, the combination 65 with the wing-shaped centrifugal surfaces of the latter, of a distributor for a uniform supply of the filling-mass onto the former having a different circumferential speed to that of the former and consisting of cones in contact with said wings and having slots at said contact points of a length corresponding to that of the latter, substantially as and for the purpose set forth.

In testimony whereof I have hereunto set 70 my hand in the presence of two subscribing witnesses.

DR. OTTO PANKRATH.
